J. SOSS.

HINGE.

APPLICATION FILED NOV. 29, 1916.

1,228,982.

Patented June 5, 1917.

Inventor

Joseph Soss,

By his Attorneys

Edgar State Co.

UNITED STATES PATENT OFFICE.

JOSEPH SOSS, OF NEW YORK, N. Y.

HINGE.

1,228,982.

Specification of Letters Patent.

Patented June 5, 1917.

Application filed November 29, 1916. Serial No. 134,015.

To all whom it may concern:

Be it known that I, JOSEPH Soss, a citizen of the United States, and residing at New York, in the county of New York and State of New York, have invented certain new and useful Improvements in Hinges, of which the following is a specification, such as will enable those skilled in the art to which it appertains to make and use the same.

This invention relates to hinges, and particularly to what are known as invisible hinges, and the object thereof is to provide an improved hinge of this class which is especially designed for use in connection with the engine hood of an automobile, but which may be used in connection with doors of any kind or class, if desired; a further object being to provide a hinge for the hood of an automobile engine which will prevent water or moisture passing in through the separate parts of the hood at the top thereof.

The invention described and claimed herein relates to hinges of the class shown and described in U. S. Letters Patent No. 880,697 granted to me March 3, 1908, and particularly to the method of using such hinges for specific purposes, and the invention is fully disclosed in the following specification, of which the accompanying drawing forms a part, in which the separate parts of my improvement are designated by suitable reference characters in each of the views, and in which:

Figure 1 is a side view of the hood of the engine of an automobile;

Fig. 2 a partial section on the line 2—2 of Fig. 1 and showing the parts of the hood in a closed position;

Fig. 3 a view similar to Fig. 2 and showing the parts of the hood in an open position, and showing one part of the hinge in section;

Fig. 4 a face view looking in the direction of the arrow 4 of Fig. 2;

Fig. 5 a side view looking in the direction of the arrow 5 of Fig. 4; and,

Fig. 6 a view similar to Fig. 2 but showing a modification.

In the drawing forming part of this specification, I have shown, in Fig. 1, the hood *a* of the engine of an automobile, and said hood comprises two side members *a*² hinged together centrally of the top of said hood at *a*³ where three of my improved

hinges are employed, and the separate side members *a*² of the hood also consist of separate parts hinged together at *a*⁴.

In the construction shown in Figs. 1 to 5 inclusive, the side members *a*² of the hood consist of sheet metal and at the top of the hood said side members are provided with inwardly directed flange plates *a*⁵ at right angles thereto, and with which my improved hinge is connected. The hinge consists of two separate similar parts, or hinge butt members *b* which are constructed and operated in the following manner. The separate parts or hinge butt members *b* are connected with the flange plates *a*⁵ by screws *c* which are passed through said flange plates *a*⁵ and through the end portions of the hinge butt members *b*, and are provided with nuts *c*², and the heads of said screws are countersunk in the flange plates *a*⁵.

The hinge butt members *b* are provided centrally thereof and on the back thereof with projecting and oblong body portions *b*², the faces or corresponding front sides of which are cut out to form oblong recesses *b*³ which open through the main butt members *b* and the top and bottom walls of which are provided with inclined grooves *b*⁴ which terminate centrally of the top and bottom walls of the recesses *b*³ in which they are formed, and the said recesses *b*³ open through the butt members *b* and through the back or outer faces of the parts *b*² thereof, and through the front faces thereof as clearly shown.

I also provide two similar sets of curved link members *d* which are alternately arranged and pivoted together at *d*² in such manner that the link members of each set comprise a longer arm *d*³ and a shorter arm *d*⁴, and the longer arms of each set of link members are connected by pins *e*, which are passed therethrough and the ends of which operate in the grooves *b*⁴, while the shorter arms of said link members are connected by pins *e*² which are passed therethrough, and which are fixed or secured in the end walls of the recesses *b*³ in the hinge butt members *b*².

One of the objects of this invention is to prevent water from entering the hood, or passing between the hinge connections of the separate parts thereof, and the hood members *a*² with their flange plates *a*⁵ may be so formed as to closely fit when the hood, or the

separate parts thereof, are in a closed position as shown in Fig. 2, and no water can enter the hood, and the separate parts of the hinge are also protected from water or moisture, and the hinge or hinges, when the separate parts of the hood are in the closed position, are entirely concealed from view.

The hinges which connect the separate parts of the side portions of the hood at α^4 10 may be made in the same manner as those employed at the top α^3 of the hood, as will be readily understood, but the hinges which connect the separate parts of the side portions of the hood at α^4 need not necessarily 15 be the same as those which connect the separate side portions of the hood at the top thereof.

In Fig. 6, I have shown a modification in which the separate side members a^2 of the 20 hood are not provided at the top thereof with the inwardly directed flange plates a^5 but in lieu thereof I provide angular plates f , the parts f^2 of which are riveted to the hood members a^2 , as shown at g , and the 25 other parts f^3 of which form the flange plates to which the hinge butt members b are secured by means of the bolts c and their nuts c^2 .

Although I have shown and described my 30 improved hinge, as applied only to the hood of automobiles, it will be understood that the same may be applied to doors of various kinds and classes, in which case, one part of the hinge will be connected with the door 35 and the other with the door jamb or frame, and when metal doors and door frames are employed, either the construction shown in Figs. 1 to 4 inclusive, or that shown in Fig. 6 may be used.

40 It will also be seen that the operative parts of the hinge herein shown and described is very similar to those of the patent hereinbefore referred to, in which the hinge is applied to ordinary doors, gates or the like, 45 but in which the flange plate members a^5 , as shown in Figs. 1 to 5 inclusive, and the corresponding flange plate members f^3 shown in Fig. 6, are not employed, and in the invention described and claimed in this application the operative or movable parts with 50

which the hinge butt members b are provided are so adjusted and so connected with said hinge butt members that when the hinge is in operation and the separate parts of the hood, or other device, are in a closed 55 position, there is a narrow space between the hinge butt members b in which the flange plate members a^5-f^3 fit, and this is the distinctive feature between the hinge described and claimed herein and that of the patent 60 referred to.

While I have shown and described the preferred form of my improvement, it will be understood that the invention is not limited to the exact details herein shown 65 and described, and changes therein and modifications thereof, may be made, within the scope of the appended claims, without departing from the spirit of my invention or sacrificing its advantages.

Having fully described my invention, what I claim as new and desire to secure by Letters Patent, is:—

1. The combination with two parts, one of which is movable and adapted to swing 75 in a predetermined arc, said parts being each provided with flange plates at right angles thereto, of a hinge consisting of separate butt members secured to the inner side of said flange plates and connected by folding and swinging parts movably connected therewith and with each other.

2. A hinge for connecting two parts, said parts being provided with flange plates at right angles thereto, and said hinge consisting of separate butt members adapted to be connected with said flange plates and which are united by separate sets of curved link members pivotally and slidably connected therewith, said butt members when in a 80 closed position being separated by a narrow space to receive said flange plates.

In testimony that I claim the foregoing as my invention I have signed my name in presence of the subscribing witnesses this 95 28th day of November 1916.

JOSEPH SOSS.
